DELAWARE.

CLIP CAP FOR SPRING COVERS.

Application filed February 5, 1924. Serial No. 690,724.

To all whom it may concern:

Be it known that we, CARLISLE A. LINCOLN and EDWIN F. ROSSMAN, citizens of the United States, both residing at Buffalo, 5 in the county of Erie and State of New York, have invented certain new and useful Improvements in Clip Caps for Spring Covers; and we do hereby declare the following to be a full, clear, and exact description 10 of the invention, such as will enable others skilled in the art to which it appertains to make and use the same.

The present invention relates to spring covers and more particularly to a cap or 15 closure forming a part of the cover and designed to enclose the upper portion of the spring clip.

In the type of spring cover or boot disclosed in the copending application of Carlisle A. Lincoln, filed November 27, 1923, 20 Serial No. 677,214, a close fitting spring cover of flexible material completely surrounds the spring and holding clips except at the upper portion of the clips where 25 openings are provided in the flexible casing for the projection of the clips therethrough. These openings are made upon application of the cover and the position is determined by the location of the clip or 30 clips in each individual spring. The closure or cap which is applied to the upper portion of the spring clip not only seals the edges of the opening but substantially covers the spring clip and presents a finished 35 appearance to the spring cover as a whole.

The object of the present invention is to provide a new and different form of clip cap or closure designed particularly for employment in connection with spring covers 40 of the above described character.

With this object in view, the several features of the invention consist in certain novel features of construction, combinations and arrangements of parts hereinafter described and claimed, the advantages of 45 which will be obvious to those skilled in the art from the following description.

In the accompanying drawings illustrating the preferred form of the invention Fig. 1 represents a top plan view of the improved form of cap applied to the spring; Fig. 2 is an end elevation partly in section of the cap shown in place upon a spring; Fig. 3 is a side elevation of the cap with the

spring cut away and shown in section; and 55 Fig. 4 is a perspective of the cap before application to the spring.

The cap or closure shown in the illustrated embodiment of the invention is designed as a single integral member which 60 may be applied to the spring clip without entirely removing the latter from the spring and which is firmly locked in position when the spring clip is completely in place. The cap comprises generally a relatively thin 65 plate of metal or other suitable material which projects beneath the cross bolt of the spring clip and bears at opposite edges upon the flexible cover casing adjacent the opening. The cap is also provided with depending wings or flanges at opposite ends which 70 are shaped to enclose the upwardly projecting legs of the spring clip and bear upon the flexible casing at opposite sides of the clip, as clearly indicated in the drawings. 75 This form of cap is readily applied by removing the cross bolt from the spring clip, inserting the cap in position with the opposite legs of the clip extending upwardly therethrough, and replacing the cross bolt 80 above the cap to lock the latter in place.

As shown in the illustrated embodiment of the invention, a spring indicated generally at 10 is provided with a spring clip 12 of the usual form. The clip 12 comprises a 85 U-shaped yoke 14 held in place upon the spring through the provision of a cross bolt 16 passing through the upper portion of the clip and locked in place by a nut 18. The spring is completely surrounded by a flexible casing 20 which also surrounds the lower portion of the spring clip 12, the casing being slit across the upper portion to permit projection of the upper portion of the spring 90 clip therethrough. The opening in the flexible casing for the accommodation of the upper portion of the clip is closed through the provision of a cap or closure member 22, which as indicated clearly in Fig. 4 consists of a plate 24 having oppositely depending 95 flanges 26. The cap is provided adjacent the ends of the plate with openings 28, through which the upper ends of the yoke 14 project, the flanges being also provided with a centrally formed bulged portion 30 to embrace the legs of the yoke and cause 100 the flanges to engage with the flexible casing at opposite sides. The plate 24 is pro-

95

100

105

vided with a central groove 32 which is adapted to be engaged by the underside of the cross bolt 16 and with downwardly inclined portions 34 which bear upon the flexible casing at opposite sides of the opening, as indicated clearly in Fig. 2. It will be evident that when this type of cap is assembled upon the spring with the cross bolt of the spring clip received in position above it, the opposite edges of the cap are caused to firmly engage with the top of the spring cover adjacent the openings and the depending flanges are caused to engage with the casing at the sides of the spring; the cap being locked firmly in place in such a manner that it cannot loosen or become disengaged.

We claim:

1. The combination with a flexible casing wrapped about a vehicle spring and having an opening for the reception of the upper portion of a spring clip of a closure member comprising a plate extending across the opening in the casing beneath the cross bolt of the spring clip and having depending portions extending downwardly along the sides of the casing, the closure member having openings for the projection therethrough of the upper portion of the spring clip.
2. The combination with a spring clip having a U-shaped yoke member and a cross bolt connected therewith of a substantially U-shaped closure member having a portion extending beneath the cross bolt of the clip, and side portions extending downwardly and partially embracing the upper portion of the U-shaped yoke, the closure member having openings for the projection therethrough of the upper ends of the yoke.
3. The combination with a vehicle spring provided with a spring clip having a U-shaped yoke member and a cross bolt of a

substantially U-shaped closure member having a portion extending beneath the cross bolt of the clip, and side portions extending downwardly and partially embracing the upper portion of the U-shaped yoke, the closure member having openings for the projection therethrough of the upper ends of the yoke.

4. The combination with a vehicle spring provided with a spring clip having a U-shaped yoke member and a cross bolt of a closure member in the form of a stamping having a portion adapted to extend across the top of the spring beneath the cross bolt and to be engaged thereby, and side portions adapted to project about and partially embrace the U-shaped yoke, the stamping being provided with openings for the projection of the U-shaped yoke therethrough.

5. A closure member for spring covers comprising a relatively thin plate having a length approximating the width of a vehicle spring and provided with a shallow groove located centrally of the plate and extending lengthwise thereof, the plate having side portions projecting substantially at right angles to the body of the plate, and openings formed in opposite ends of the plate, the walls of the openings being formed in part by a central bulge in the side portions.

6. A closure member for spring covers comprising a centrally grooved plate, the length approximating the width of a vehicle spring, having flanged portions projecting from opposite ends of the plate and having offset or bulged parts intermediate the edges, and openings formed in the ends of the plate and partially surrounded by the bulged portions of the flanges.
